UNITED STATES PATENT OFFICE.

TANDY A. BRYSON, OF TROY, NEW YORK, ASSIGNEE TO TOLHURST MACHINE WORKS,
A CORPORATION OF NEW YORK.

CENTRIFUGAL DRYING-MACHINE.

1,311,871.

Specification of Letters Patent.

Patented Aug. 5, 1919.

Application filed November 13, 1916. Serial No. 131,182.

To all whom it may concern:

Be it known that I, TANDY A. BRYSON, a citizen of the United States, and a resident of Troy, New York, have invented new and useful Improvements in Centrifugal Drying-Machines, of which the following is a specification.

The invention relates to centrifugal machines, or hydro-extractors, and more particularly to such machines which are mounted to have horizontal equilibrating movement to adjust or compensate for uneven loading.

Objects and advantages of the invention will be set forth in part hereinafter, and in part will be obvious herefrom, or may be ascertained from practice with the invention.

The invention consists in the novel parts, constructions, arrangements, combinations and improvements herein shown and described.

The accompanying drawings, herein referred to, and constituting a part hereof, illustrate one embodiment of the invention, and together with the description serve to explain the principles thereof.

Of the drawings:—

Figure 1 is a central vertical section of a machine embodying the invention; and

Fig. 2 is a plan of such a machine.

Referring to the machine of the accompanying drawings, illustrating by way of example one embodiment of the invention, multipoint, flexible or horizontally movable supporting means for the rotating basket are provided, disposed around and at the general level or horizontal central line of the basket. This contributes largely to the stabilizing of the machine, permits the use of parts of less weight, and eliminates harmful strain and friction, and also leaves the top of the basket entirely free and unobstructed by machine parts, and greatly facilitates the loading and other manipulation of the machine.

In the embodied form, there are provided, symmetrically arranged about the machine, three standards 1, 2 and 3, mounted upon and secured to the floor or some suitable base. The casing is supported therefrom by horizontally movable ball and socket joints. As embodied, each of the standards has at its top an over-hung head 4 which has an

upwardly-opening, spherically cupped recess 5, and below such recess, and opening downwardly therefrom, an aperture or hole 6, increasing in diameter in the downward direction.

Located within the standards 1, 2 and 3 is a casing 7, of general cylindrical form, within which casing is the rotating basket for holding the material to be dried. Upon the outside of the casing 7 are three symmetrically disposed lugs 8, 9 and 10, the lugs 65 being positioned preferably substantially centrally of the height of the casing. Each of these lugs has upon its bottom side a downwardly opening, spherically cupped recess 11, and opening upwardly therefrom 70 an aperture or hole 12, increasing in diameter in the upward direction.

The overhung heads 4 of the respective standards 1, 2 and 3 and the corresponding lugs 8, 9 and 10 on the casing are connected 75 by links 13, thereby providing a multipoint, horizontally swinging suspension for the casing 7 and the rotatable basket therewithin. Links 13 comprise respectively rods 14, passing through the corresponding standard head 4 and casing lug 8, 9 or 10. Nesting within the spherical cup of each head is a hemi-spherically shaped piece 15, and a similarly shaped piece 16 rests within the cup 11 of the casing lug. The corresponding rod 14 passes through central apertures in the hemi-spherical pieces 15 and 16, and has suitable fastening means at its ends, preferably nuts 17 and 18, taking on to the threaded ends of the rods 14. By this 90 mounting or suspension the casing is left free to move horizontally, but is firmly and smoothly carried by the links in any position and during the shifting movement, and the points of suspension are approximately 95 in the horizontal line of the rotating load in the basket.

Means are provided by the invention, cooperating with the means already described and comprising certain features of the 100 mounting of the rotating basket, or equilibrating an unbalanced rotating load, and for preventing dancing or chattering on the suspending links, heating of the bearings, and thumping or pounding of the basket shaft. 105

In the embodiment of such means, and referring particularly to the mounting of the basket in the casing, the bottom 20 of the

casing 7 is upwardly inclined inwardly, and has one or more outlets 23. The casing floor terminates in an upwardly extending flanged hub 21. The hub 21 has a central aperture 22 of conical form with the diameter decreasing in the downward direction, the aperture serving as a seat for the housing of the basket shaft.

The basket 24 may be of usual form, having vertical side walls 25, and having at the top an overhanging lip or flange 26. The bottom 27 of the basket is also upwardly inclined inwardly toward its center, and has at its central portion a bell-shaped upward projection 28. The part 28 terminates in a hub 29, which hub is centrally apertured, the aperture decreasing conically upwardly, to form a seating for the basket upon its shaft.

The basket shaft 35 at its upper end is tapered decreasingly upwardly to fit the basket hub 29, the basket being angularly fixed to its shaft in any suitable manner. A cap piece 34, provided preferably with an oil cup, covers the end of the shaft and is fastened to hub 29. Encircling shaft 35 below the basket hub 29 is a housing 36, the housing being outwardly conically formed to seat within the hub 21 of the suspended casing 7, as shown in Fig. 1. The housing 36 is held against rotation relatively to the casing 7 by suitable means, such as a set screw 37 nesting in a recess in the casing hub 21.

Housing 36 is provided with both radial and horizontal or thrust bearings for the rotating shaft 35.

A radial bearing 38 is provided, preferably substantially on the horizontal level of the points of suspension of the casing 7, as shown in Fig. 1. The bearing comprises an inwardly extending shoulder 39 on the shaft, taking over a horizontally disposed ring 40 encircling the shaft. On its exterior the ring 40 is grooved to form a race for a series of balls 41. The balls 41 are encircled exteriorly by a grooved, horizontally disposed ring 42. The ring 42 in turn is seated on an inwardly projecting shoulder 43 formed on the interior of the housing 36. A suitable cap 44 encircles shaft 35 and fits over the top of the housing 36. The radial bearing is thus in the same horizontal plane with the center of gravity of the basket and load.

A horizontal thrust or sustaining bearing within the housing for the shaft and basket is provided, comprising an inwardly extending shoulder 45 on the shaft, seated on a ring 47 encircling the shaft. Ring 47 is seated on a ring 48, which in turn rests upon horizontally arranged rollers 49. Rollers 49 rest upon a flat ring 50, the ring encircling shaft 35 and resting upon an inwardly projecting shoulder 51 formed on the housing 36. The basket 25 and its vertical shaft 35 are thus rotatively supported by the horizontally movable non-rotating casing 7.

Another radial bearing for shaft 35 is provided, at or near the bottom of the housing 36, and preferably at the point of drive for shaft 35. As embodied, shaft 35 is inwardly shouldered at 54, the shoulder resting on a ring 55, which ring encircles the shaft 35 and has on its exterior a raceway for an annular series of balls 56. Encircling the balls 56 is a ring 57, grooved within to form a raceway for the balls. A cap 59 encircles shaft 35 and is fastened to housing 36 to support the bearing members in position. By having one radial bearing at approximately the center of gravity of the basket and its load, and the other radial bearing in line with the belt pull, the eccentricity of bearing load is reduced to a minimum.

The embodied driving means for the basket shaft comprises a pulley 60 fixed to the end of shaft 35, just below the lower radial bearing. As shown pulley 60 has a taper fit on shaft 35, its hub 68 being angularly fixed to the shaft by a set screw 61, and being held on the shaft by a nut 62. A pulley brake 64 is shown in part by 64. Pulley 65 is journaled in supporting arms 66, which arms are fixed to a plate 67, supported by the casing 7.

From the foregoing it will be seen that the points of suspension are substantially on the horizontal center line of the basket, and that the radial thrust due to an unbalanced load is taken up on the radial bearing substantially in the horizontal line or level of the points of suspension of the casing and of the center of the basket. Thus the centrifugal force due to the unbalanced load tends to cause a motion of translation of the case, and not to tip it and to successively and rapidly lift it from one suspension after another, which is the cause of dancing and chattering of the supports and pounding of the shaft. The horizontal alignment of the shaft bearing and points of suspension tends to eliminate any vertically disposed moment or momentum arm of the unbalanced load vertically along the shaft, and obviates the necessity of oppositely disposed excess weight to counteract the consequent tipping tendency. By my construction, the inertia is reduced to a minimum, and the freedom to gyrate and find a balanced center of rotation (non-coincident with the mechanical or geometric center) due to the unbalanced load is practically a maximum. That is, for a given permissible stress on the bearings, the unbalanced load which may be safely carried is maximum.

The invention in its broader aspects is not limited to the precise form shown and described, but variations may be made therein without departing from the principles of the invention and without sacrificing its chief advantages.

What I claim as my invention and desire to secure by Letters Patent is:—

1. A centrifugal drying machine including in combination, a casing, a rotatable basket within the casing, a plurality of horizontally movable casing supporting devices connected to the casing in a horizontal plane substantially through the middle portion of the basket.
- 10 2. A centrifugal drying machine including in combination a casing having a multi-point horizontally movable suspension, a rotating basket within the casing, a shaft supported by the casing, a radial bearing between the shaft and casing approximately in a horizontal plane through the points of suspension on the casing.
- 20 3. A centrifugal drying machine including in combination a casing having a horizontally movable suspensor attached to the casing at a plurality of points, a rotating basket within the casing, a shaft supported by the casing, a radial bearing between the shaft and casing approximately in a horizontal plane through the center of gravity of the basket and load.
- 30 4. A centrifugal drying machine including in combination a casing having a multi-point suspension, a rotating basket within the casing, a shaft supported by the casing, a radial bearing between the shaft and casing approximately in a horizontal plane through the points of suspension on the casing and another radial bearing having a belt pulley carried by the shaft approximately in the same horizontal plane with said bearing.
- 40 5. A centrifugal drying machine including in combination a casing having a multi-point horizontally movable suspension, a rotating basket within the casing, a shaft supported by the casing, a radial bearing between the shaft and casing approximately in a horizontal plane through the center of gravity of the basket and load and another radial bearing having a belt pulley carried by the shaft approximately in the same horizontal plane with said bearing.
- 50 6. A centrifugal drying machine including in combination a casing having a multi-point horizontally movable suspension, a rotatable basket within the casing, a shaft for the basket, a housing for the shaft fitting into the center of the casing with a downwardly decreasing taper fit.
7. A centrifugal drying machine including in combination a casing having a multi-point horizontally movable suspension, a rotatable basket within the casing, a shaft for the basket, a housing for the shaft, said housing being carried by said casing and two separated radial bearings within said housing.
- 15 8. A centrifugal drying machine including in combination a casing having a multi-point horizontally movable suspension, a rotatable basket within the casing, a shaft for the basket, a housing for the shaft, said housing being carried by said casing and two separated radial bearings within said housing, one of said radial bearings being substantially in the same horizontal plane with the center of gravity of the basket and its load.
- 25 9. A centrifugal drying machine including in combination a horizontally movable, externally supported casing, a rotatable basket within the casing and having a shaft, a housing for the shaft supported by the casing and carrying a plurality of radial bearings, one of said bearings being approximately in the same horizontal plane with the center of gravity of the basket and load and another of said radial bearings having a belt pulley carried by the shaft approximately in the same horizontal plane with said bearing.
- 35 10. A centrifugal drying machine including in combination a horizontally movable, externally supported casing, a rotatable basket within the casing, a shaft for the basket, a housing provided with a plurality of bearings for the shaft, the housing being supported by the casing and located within and beneath the basket bottom and fitting into the center of the casing, to be supported thereby, with a downwardly decreasing taper fit.
- 45 11. A centrifugal drying machine including in combination a horizontally movable, externally supported casing, a rotatable basket within the casing, a shaft for the basket, an integral housing having therewithin a plurality of spaced-apart bearings for the shaft, said housing being located within and beneath the basket bottom and supported by the casing.

In testimony whereof I have signed my name to this specification in the presence of two subscribing witnesses.
